SHIRT HOLD-DOWN DEVICE

Frank R. Sinopoli, San Diego, Calif.

Application November 25, 1946, Serial No. 712,079

8 Claims. (Cl. 2—323)

1

My invention relates to a shirt hold-down device, more particularly for use in inter-connected relation with a person's shirt and trousers and the objects of my invention are:

First, to provide a shirt hold-down device of this class which is entirely hidden from view when in connected relation with a person's shirt and trousers;

Second, to provide a shirt hold-down device of this class which very efficiently maintains a person's shirt in neat straight position relatively to the trousers in which the tail of the shirt is positioned;

Third, to provide a shirt hold-down device of this class which may be used in connection with conventional shirts and trousers without alteration of either the shirt or the trousers;

Fourth, to provide a shirt hold-down device of this class which is very simple and easy to apply in connected relation with a shirt and trousers;

Fifth, to provide a shirt hold-down device of this class which may be very quickly and easily released from its connected relation with a shirt and trousers;

Sixth, to provide a shirt hold-down device of this class which is very thin and light, preventing undue strain in connection with a shirt and trousers;

Seventh, to provide a shirt hold-down device of this class which is entirely connected to the thread supporting buttons in connection with a shirt and trousers; and

Eighth, to provide a shirt hold-down device of this class which is very simple and economical in construction, efficient in operation and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawings and to the characters of reference thereon forming a part of this application in which:

Fig. 1 is a front elevational view thereof showing by dash lines the connected relationship therewith of a shirt and trousers; and Fig. 2 is an edge elevational view thereof showing by dash lines the connected relationship thereof with a shirt and trousers.

Similar characters of reference refer to similar parts and portions throughout the drawing.

The shirt hook 1, trouser hook 2, strap 3, and

2

the clip 4 constitute the principal parts and portions of my shirt hold-down device.

The shirt hook 1 is arranged to engage the thread G connecting the button E to the shirt overlapping portion A. This shirt hook 1 is provided with a U-shaped portion 1a adapted to fit over the thread G integral with which is an angularly disposed guide portion 1b adapted to facilitate the placement of the U-shaped portion 1a over the thread G all as shown best in Fig. 1 of the drawing. The opposite end of this shirt hook 1 is provided with a strap supporting portion 1c disposed substantially in perpendicular relationship with the axis of the U-shaped portion 1a arranged to engage the loop portion 3a of the strap 3 all as shown best in Fig. 2 of the drawing. The strap 3 is preferably of elastic material but may be made of any other suitable material as desired. This strap 3 is adjustably secured by means of the clip 4 which is a conventional strap clip arranged to provide longitudinal adjustment on the strap 3 as desired. The opposite end of the strap 3 is connected with a strap engaging loop portion 2a of the trouser hook 2. This trouser hook 2 is provided with a substantially U-shaped offset portion 2b arranged to extend around the overlapping portion B of the shirt as indicated by dash lines in Fig. 1 of the drawing. This offset U-shaped portion 2b is normally positioned below the upper edge J of the overlapping portions C and D of the trousers. This relationship is maintained by the position of the button F secured to the trousers by the thread H around which the hook portion 2c of the trouser hook 2 is engaged. This button F is the conventional button securing the upper overlapping portions of the trouser fly. The hook portion 2c of the trouser hooks 2 is substantially U-shaped and provided with an angularly disposed end portion 2d arranged to facilitate the placement of the hook portion 2c over the thread H in connection with the conventional button F which is secured to the frontal overlapping portion C of the trousers. It will be here noted that the U-shaped offset portion 2b, as shown in Fig. 2 of the drawing, passes around the outer edge of the overlapping portion B of the shirt and to the front side thereof, as shown best in Fig. 2 of the drawing, and engages the thread H in connection with the button F forwardly of the overlapping portion B of the shirt below the upper edge of the trousers.

The operation of my shirt hold-down device is substantially as follows:

In connecting my shirt hold-down device to a

shirt and trousers, the shirt hook 1 at its U-shaped portion 1a is first fitted over the thread connecting the button E to the rearmost overlapping portion A of the shirt, thus, the shirt hook 1 is entirely hidden between the overlapping portions A and B of the shirt and extends downwardly therebetween in connection with the strap 3 which suspends the trouser hook 2 at a position below the upper edge J of the trousers. After the shirt hook 1 has been properly connected to the shirt as hereinbefore described, the trouser hook 2 at its offset U-shaped portion 2b is placed around the outer edge B' of the overlapping portion B of the shirt whereby the hook portion 2c of the trousers 2 is placed at the front side of the overlapping portion B of the shirt below the upper edge J of the trousers and engaged with the thread H connecting the button F to the front overlapping portion C of the trousers. The elastic character of the strap 3 maintains slight tension intermediate the buttons E and F of the shirt and trousers respectively, whereby the shirt is held in neat, straight, flat position at the front side of the wearer and is prevented from billowing out over the upper edge J of the trousers. This shirt hold-down device is quickly disconnected from the trousers by simply shifting the hook portion 2c thereof laterally of the thread H connecting the button F to the front overlapping portion C of the trousers permitting the shirt or trousers to be removed individually as desired.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is.

1. The combination with overlapping portions of a shirt and trousers of a U-shaped hook member adapted to be placed intermediate the overlapping portions of said shirt, a button connecting said overlapping portions, said hook engageable with the thread connecting said button to the innermost overlapping portion of said shirt adjacent the upper edge of said trousers, a strap in connection with said hook member, a second hook member having a U-shaped offset portion in connection with said strap adapted to extend around the edge of the outermost overlapping portion of said shirt, a trouser button, said second-mentioned hook member provided with a hook portion integral with said U-shaped offset portion adapted to be positioned at the front side of the overlapping portions of said shirt and engage said trouser button at the inner side of said trousers substantially below the upper edge thereof.

2. In a shirt hold-down device of the class described, the combination with overlapping portions of a shirt and an inwardly extending button in connection with the trousers of a hook portion adapted to be positioned intermediate the overlapping portions of said shirt engageable with button connecting thread secured to said shirt, a strap in connection with said hook, a second hook member having a U-shaped offset portion in connection with said strap adapted to extend around the edge of the front overlapping portion of said shirt, said second-mentioned hook

provided with a substantially U-shaped hook portion integral with said U-shaped offset portion positioned at the front side of said shirt and engageable with the inwardly extending button in connection with said trousers.

3. In a shirt hold-down device of the class described, the combination with overlapping portions of a shirt and an inwardly extending button in connection with the trousers of a hook portion adapted to be positioned intermediate the overlapping portions of said shirt engageable with button connecting thread secured to said shirt, a strap in connection with said hook, a second hook member having a U-shaped offset portion in connection with said strap adapted to extend around the edge of the front overlapping portion of said shirt, said second-mentioned hook provided with a substantially U-shaped hook portion integral with said U-shaped offset portion positioned at the front side of said shirt and engageable with the inwardly extending button in connection with said trousers, said U-shaped offset portion of said second-mentioned hook positioned below the upper edge of said trousers.

25 4. In a shirt hold-down device of the class de-
scribed, the combination with overlapping por-
tions of a shirt and an inwardly extending but-
ton in connection with the trousers of a hook
portion adapted to be positioned intermediate the
30 overlapping portions of said shirt engageable with
button connecting thread secured to said shirt,
a strap in connection with said hook, a second
hook member having a U-shaped offset portion
in connection with said strap adapted to extend
35 around the edge of the front overlapping portion
of said shirt, said second-mentioned hook pro-
vided with a substantially U-shaped hook por-
tion integral with said U-shaped offset portion
positioned at the front side of said shirt and en-
40 gageable with the inwardly extending button in
connection with said trousers, said U-shaped off-
set portion of said second-mentioned hook posi-
tioned below the upper edge of said trousers,
said strap being made of elastic material.

45   5. In a shirt hold-down device of the class de-
scribed, the combination with overlapping por-
tions of a shirt and an inwardly extending but-
ton in connection with the trousers of a hook
portion adapted to be positioned intermediate the
50 overlapping portions of said shirt engageable with
button connecting thread secured to said shirt,
a strap in connection with said hook, a second
hook member having a U-shaped offset portion in
connection with said strap adapted to extend
55 around the edge of the front overlapping portion
of said shirt, said second-mentioned hook pro-
vided with a substantially U-shaped hook por-
tion integral with said U-shaped offset portion
positioned at the front side of said shirt and
60 engageable with the inwardly extending button
in connection with said trousers, said U-shaped
offset portion of said second-mentioned hook po-
sitioned below the upper edge of said trousers,
said strap being made of elastic material and a
65 clip in connection with said strap for longitudi-
nally adjusting the same.

6. In a shirt hold-down device of the class described, the combination of a shirt hook having a U-shaped portion at its normally upper end and a strap connection portion at its normally lower end, a strap in connection with the strap connection portion of said shirt hook, a trouser hook in connection with the normally lower end of said strap having an offset portion adapted to 70 surround the outer edge of the front overlapping 75

portion of a shirt, said trouser hook having a substantially U-shaped hook portion adapted to be positioned at the front side of the foremost overlapping portion of a shirt and engage an inwardly extending button in connection with trousers adjacent said shirt.

7. In a shirt hold-down device of the class described, the combination of a shirt hook having a U-shaped portion at its normally upper end and a strap connection portion at its normally lower end, a strap in connection with the strap connection portion of said shirt hook, a trouser hook in connection with the normally lower end of said strap having an offset portion adapted to surround the outer edge of the front overlapping portion of a shirt, a button having thread connecting the same to said shirt engaged by said shirt hook said trouser hook having a substantially U-shaped hook portion adapted to be positioned at the front side of the foremost overlapping portion of a shirt and engage an inwardly extending button in connection with trousers adjacent said shirt, said offset portion of said trouser hook positioned below the normally upper edge of said trousers.

8. In a shirt hold-down device of the class described, the combination of a shirt hook having a U-shaped portion at its normally upper end and a strap connection portion at its normally lower

end, a strap in connection with the strap connection portion of said shirt hook, a trouser hook in connection with the normally lower end of said strap having an offset portion adapted to surround the outer edge of the front overlapping portion of a shirt, a button having thread connecting the same to said shirt engaged by said shirt hook said trouser hook having a substantially U-shaped hook portion adapted to be positioned at the front side of the foremost overlapping portion of a shirt and engage an inwardly extending button in connection with trousers adjacent said shirt, said offset portion of said trouser hook positioned below the normally upper edge of said trousers, said shirt hook and said trouser hook having angularly disposed portions in connection with said U-shaped portions adapted to facilitate the placement thereof in connection with the thread securing buttons to said shirt and said trousers.
